FLUID PRESSURE OPERATED CURB
SIRUP SEPARATOR

Charles A. Olcott, West Milford, N. J.

Application February 1, 1944, Serial No. 520,604

13 Claims. (Cl. 210—75)

1

This invention relates to centrifugal apparatus and more particularly to centrifugal separators of the kind employed in the refining of sugar. In a specific aspect, the invention relates to methods of and apparatus for separating "green syrup" and "wash syrup" in sugar centrifugals.

An object of the present invention is to provide improved methods of and apparatus for classifying two or more types of fluids by directing them into separate containing means.

In sugar refining, precipitated sugar crystals dispersed through a mass of the molasses-like mother liquor are usually separated from or purged of the adhering fluid by centrifugal action in a centrifuge or centrifugal comprising a rotatable basket with perforated side walls through which the adhering fluid is in large measure expelled or spun off as "green syrup." Inasmuch as the initial purging is not quite effective to free the crystals of all of the adhering molasses, it is the practice to remove the residue by washing the sugar with hot water or steam while still in the centrifuge and to remove the resulting "wash syrup" by further centrifuging. Both the green syrup that is first removed and the wash syrup that is removed immediately thereafter contain dissolved sugar but, in view of the fact that the two syrups have different degrees of purities, quite different processes are required for the subsequent efficient recovery of their respective sugar values and for this reason it is imperative that the two syrups be separately collected and that mixing of the two even within the centrifuge be minimized.

Another object of the present invention is to provide a centrifuge of the kind described which is provided with means to effect improved separation of the green and wash syrups, these two syrups being in practice called "curb" liquids or syrups.

Heretofore, centrifuges have on occasion been provided with separate interior collecting troughs or gutters for the two types of fluid expelled, and an interior movable guide member, sometimes called a "classifier," which may be moved from one position to another to guide the centrifuged fluids that successively flow down the interior wall or curb of the centrifuge casing to their respective collecting troughs.

In accordance with the present invention, this separation of the curb liquids is accomplished without requiring that moving parts which come in contact with the syrup be provided. The advantages of a separating arrangement which does not employ such moving parts are self-evident.

2

In a specific embodiment of the invention, shown and described by way of example for purposes of illustration, fluid pressure is utilized to effect the separation of the two kinds of liquids. 5 In this embodiment the annular opening at the top of the outer gutter (the wash syrup gutter) is made very narrow, as, for example, one eighth inch or even less. This opening is large enough, however, to cause any syrup subjected to the 10 whirling action of the air and syrup inside the curb, especially thin wash syrup, to flow through this opening rather than into the inner annular gutter if there were nothing to prevent such flow. To control this action, means are provided to 15 force a suitable gas or vapor into the outer gutter during that portion of the centrifuge cycle when the green syrup is being spun off from the centrifugal basket to raise the pressure in the gutter above atmospheric pressure and thus to 20 prevent the green syrup from flowing into that gutter. When it is desired to have the wash syrup flow into the outer gutter, the positive pressure means is removed from that gutter or by suction means the pressure therein is made less 25 than atmospheric pressure. The fluid used for raising the pressure in the outer gutter is preferably low pressure steam or a mixture of air and steam. By using steam, it is possible to supply heat and humidity to this gutter to facilitate 30 the flow of the syrup as well as to raise the pressure in the gutter.

The annular opening in the top of the outer gutter can be effectively decreased in length by providing a number of interrupters distributed 35 over the circumference of the opening or used to plug spaced portions of the opening. The interrupters preferably converge upwardly to a peak or ridge so that syrup flowing down the wall of the curb is directed to the openings between the 40 interrupters.

While the invention in a primary aspect relates to the utilization of fluid pressure to effect the separation of the two kinds of fluids without using any moving parts which come in contact 45 with the syrup, in another of its aspects the invention is applicable to mechanical types of curb liquid separators used heretofore. As separators of the mechanical type may, after a time, develop leaks due to various causes, the application of fluid pressure in the outer gutter during the proper portion of the centrifuge cycle prevents these leaks from admitting green syrup into the wash syrup gutter.

The invention will be more readily understood 50 by referring to the following description taken in

connection with the accompanying drawings forming a part thereof, in which:

Fig. 1 shows in partial cross section a centrifuge incorporating a curb syrup classifier employing fluid pressure in accordance with the invention; and

Figs. 2 to 5, inclusive, show details of various modifications of the arrangement shown in Fig. 1.

Referring more specifically to the drawings, Fig. 1 shows, by way of example for illustrative purposes, a fluid pressure-operated curb syrup separator for centrifugal machines used in the manufacture of sugar. The centrifugal machine comprises the usual basket 10 with perforated side walls, the basket being suspended at the lower end of a vertical drive shaft 11 within a suitable housing or casing. In the centrifuging operation, the molasses and wash fluids successively introduced into the basket are cast off through the lateral perforations while the crystalline sugar builds or "walls" up on the interior face of the basket. The centrifuged fluids are thrown against the interior casing wall or curb 12 and flow down its face for collection in and discharge from one or another of a plurality of concentric annular troughs or gutters 13 and 14. These gutters are separated and partially bounded by a vertical annular wall or partition 15. At its upper extremity the partition 15 is caused to slope outwardly and upwardly to form a flange 16 which extends almost to the inner surface of the curb wall 12, leaving a very narrow annular gap or opening 17 between the members 16 and 12. This gap affords a passageway for curb syrups destined for the outer trough 14. Wash fluid is provided by means of the pipe 18 terminating in an opening 19. A valve 20 is provided to control the flow of the wash fluid.

In the arrangement shown in Fig. 1, the opening 17 is made as small as possible. It may be one eighth inch or even less because the whirling action of the air and syrup inside the curb 12 will cause any syrup, especially thin wash syrup, to flow through this opening into gutter 14 rather than to flow into gutter 13 (provided there is nothing to prevent such flow). To control this action, means is provided to force a suitable gas or vapor through conduit 21 into gutter 14. This means may comprise a low pressure steam pipe 22, for example, but other gases or vapors may be used instead of steam, if desired. The outlet 23 of gutter 14 is trapped at its lower end 24, as by having it discharge into trough 25 in which the level of the syrup is always maintained at a point 26 which is considerably above the end 24 so that the fluid being forced through conduit 21 into the gutter 14 will of necessity have to pass out through the annular opening 17. The amount and pressure of the fluid being forced into the gutter 14 is made sufficient to maintain the fluid pressure within this gutter higher than the air pressure in the curb 12 plus a small pressure caused by the weight of molasses (syrup) which would accumulate at the opening 17. By this means, the molasses cannot flow through the opening 17 into the gutter while fluid from the pipe 22 is passing into the gutter 14. The level 27 of the liquid in the outlet 24 is, of course, lower than the level 26. When steam is used as the fluid-pressure supplying means, heat and humidity are also supplied by the steam to the syrup to facilitate its flow.

Conduit 21 is provided with a valve 28 or other suitable control means so that the flow of fluid

from the source 22 to the gutter 14, increasing the pressure therein, may be cut off whenever it is desired to allow the wash syrup to flow into the gutter 14. Normally the green syrup is more viscous than the wash syrup so that the small opening 17 would normally not permit more than a small amount of green syrup to flow into gutter 14 even if the increase in fluid pressure were not provided. The increased pressure in accordance with this invention is sufficient to entirely prevent such flow. The pressure supplied by the pipe 22 is preferably slightly higher than the air pressure inside the curb 12 at the opening 17. This pressure will vary according to the dimensions of the centrifugal basket and curb and the speed of the centrifugal. In practice, the pressure is readily measured by a gauge tapped in the side of the curb 12 above the opening 17 and the pressure in the source 22 is adjusted to give a slightly higher pressure within the gutter 14, which pressure is similarly measured.

The arrangement of Fig. 1 operates as follows: When the centrifugal machine is started by suitable automatic or manual means, the valve 28 is turned (substantially simultaneously with the starting) to the open or "on" position to permit the steam from the source 22 to flow into the outer gutter 14. The green syrup being spun off the sugar grains by the rotation of the basket 10 passes through the small apertures in the basket and strikes the curb 12 and flows down it toward the gutters 14 and 13, the flow being facilitated by the heat and humidity provided by the steam. Due to the increased pressure in the gutter 14 caused by the steam, the syrup does not pass through the opening 17 into this gutter but passes instead to the gutter 13. After a suitable time interval the wash water or other fluid in the pipe 18 is turned on by moving valve 20 and, after a very short time interval sufficient to wash the green syrup off the curbing wall, the valve 28 is turned to the "off" position. Closing this valve not only cuts off the steam pressure from the gutter 14 but also has the effect of causing a partial vacuum within the gutter 14 due to the steam condensing. Thus the pressure in the curb 12 outside the gutter 14 is at least as great as (and usually greater than) the pressure within and the wash syrup flows by gravity into this gutter. After another suitable time interval, the length of which is determined by the time necessary to wash the sugar to the desired color and purity without unnecessary wasting of sugar by needless washing, the wash fluid is cut off and the centrifugal allowed to rotate a little while longer to dry the sugar. After the drying period, the centrifugal is braked and unloaded. While the various steps of (1) starting the centrifugal and turning the valve 28 to the "on" position, (2) turning on the wash fluid in the pipe 18 by moving the valve 20 to its "on" position, (3) turning the valve 28 to the "off" position, (4) cutting off the wash fluid by moving the valve 20 to its "off" position, and (5) the stopping of the centrifugal by cutting off the power and applying the brake may be performed at the proper time by manual means, preferably an automatic controller 29, of any suitable type, is provided to cause the actuation of the various elements at the proper times. The controller 29 for simplicity in the drawing has been represented as a box with various mechanical or electrical connections 30, 31, 32 and 33 (represented schematically as dashed lines) leading therefrom to the valve 28 to the valve 20 in the wash fluid pipe

18, to the driving means for the centrifugal and to the brake mechanism therefor, respectively. By way of example, an automatic controller of the type shown in Patent 1,947,679 issued Feb. 20, 1934, to R. A. Steps can be used to cause the various steps described above to be performed at the proper time.

If the opening 17 extends all the way around the curb 12, a considerable amount of air is required to maintain the desired pressure in gutter 14. In order to reduce the amount of air required, spaced plugs or interrupters 34 are provided in or above the annular opening 17 to divide this opening into a large number of circumferentially spaced openings. The members 34 are held in position by any suitable means and may be integral with the curb 12. As shown in Figs. 2 and 3, which are enlarged partial cross-section views, these interrupters 34 reduce by about 50% that portion of the opening 17 through which air can pass. Each of the plugs or interrupters 34 preferably converges upwardly to a peak or ridge, as shown in Fig. 2, so that molasses flowing down the wall of the curb 12 is directed to the openings between the interrupters.

Fig. 4 shows a modification wherein the outlet from the gutter 14 is taken from the same pipe 35 which feeds the fluid (steam, for example) to the gutter 14. The outlet pipe 36 is trapped at its lower end 37, as by having it discharge into a trough 38 in which the level is always maintained at a point 39 which is considerably above the end 37 so that the fluid being forced through conduit 35 will have to pass into the gutter 14 and out through the opening 17. The level 40 of the liquid in the pipe 36 is, of course, lower than the level 39, this being due to the fluid pressure. The arrangement of Fig. 4 has the advantage over that of Fig. 1 in that only one opening (35) into the gutter 14 is required rather than the two (21 and 23) in the arrangement of Fig. 1.

After the green syrup has been spun off and caused to flow into the gutter 13 and the wash water is being applied by the pipe 18, thus causing the wash syrup to be spun off, it is sometimes desirable to encourage its flow into the gutter 14 by more positive means than by merely removing the increased fluid pressure from the source 22. This can be accomplished by applying a negative pressure or suction to the pipe 35 by any suitable means. By way of example, a pump 41 (see Fig. 5) can be provided to make the pressure in the gutter 14 less than that in the curb 12 when it is desired to have the wash syrup flow into the gutter 14. A valve 42 can be provided in the pipe connection 43 leading to the pipe 35 and this valve can be controlled with the valve 28 in the pipe 21 by a member 44 in such a way that as the valve 28 is closed the valve 42 is opened, and vice versa. The operation of the valves 28 and 42 can be controlled by hand or by any suitable timing means such as the automatic controller 29 described above in connection with the arrangement of Fig. 1. Valve 28 is open, causing the fluid pressure in gutter 14 to rise, while green syrup is being spun off, valve 42 being closed during this interval. Valve 28 is closed and valve 42 is open during the time the wash syrup destined for the gutter 13 is being spun off, thus causing the lowering of the pressure in the gutter 14 to below atmospheric pressure by the action of the pump (negative pressure means) 41. Fig. 5 also shows an air blower 45 for forcing air at a pressure comparable to that of the steam in the pipe 21 into the pipe 35 at the same time that

the steam is applied thereto and mixed therewith. The blower 45 is connected by means of a pipe 46 to the conduit 47 leading to the entrance pipe 35 and a valve 48, preferably operated in synchronism with the valve 28 by the member 44, is provided in the pipe 46. As an alternative, the steam is not used and only the air from the blower 45 is utilized to increase the pressure in the gutter 14. If the steam is not used, the air from the blower 45 can be heated and/or humidified by any suitable means (not shown), if desired. Except for the changes mentioned above, the operation of the arrangement shown in Fig. 5 is like that described above in connection with Fig. 1. It should be noted that during the suction part of the cycle the level of the syrup in the outlet pipe 36 rises to a level 49 (shown by dash lines in Fig. 5) which is higher than either of the levels 39 and 40.

The principle of providing an increased fluid pressure inside the gutter 14 can also be used advantageously with the mechanical types of syrup separators commonly used. This separator, as explained above, may develop leaks due to various causes, and supplying a fluid at increased pressure prevents these leaks from admitting green syrup into the wash syrup-gutter 14.

Various changes and modifications other than those specifically mentioned above may be made without departing from the spirit of the invention, the scope of which is indicated by the appended claims. In the claims, the term "fluid" is intended to be broad enough to cover a mixture of two or more fluids as well as a single fluid.

What is claimed is:

1. The method of directing two liquids which successively flow through the same space in different time intervals into different ones of two containers, said containers being provided with directing means, which directing means and containers are so located with respect to each other and to said space that any liquid in said space normally flows therefrom into the first container only, which comprises applying a fluid pressure in the first container, during the time interval that the first of said liquids is flowing through said space, which is sufficiently high to deny said first liquid access to said first container and to act in cooperation with said directing means to cause said first fluid to flow into the second container, and thereafter reducing the fluid pressure, during the time interval that the second of said liquids is flowing through said space, to a value which is sufficiently low so that liquid access to said first container is no longer denied, whereby said second liquid flows into said first container.

2. The method of separating green syrup from wash syrup in a sugar centrifugal comprising a rotatable mesh basket, a container therefor provided with two annular gutters, one outside of the other, for collecting the syrups, the two gutters being so located with respect to the rest of the container that all the syrup normally flows into said outer gutter only, and means between the gutters for directing syrup toward the inner gutter whenever the flow thereof into the outer gutter is blocked, which comprises the steps of applying a fluid pressure in the outer gutter during that portion of the centrifuging cycle that the green syrup is being spun off which is sufficiently high to prevent the green syrup from entering said outer gutter, whereby the green syrup is directed by said directing means into the inner gutter, and then reducing the fluid pressure in said

outer gutter to a pressure which is sufficiently low to allow syrup to flow therein during at least a part of that portion of the centrifuging cycle that the wash syrup is being spun off.

3. In combination, a container for liquids comprising inner and outer annular troughs at the base thereof, centrifugal means above said troughs for causing liquid to flow in said container toward said troughs, said troughs being so positioned with respect to said liquid flow that the liquid normally flows into the outer trough only, directing means between said troughs adapted to direct the liquid into the inner trough, and means for applying fluid pressure in the outer trough to such an extent that liquid from said centrifugal means is prevented from flowing into the outer trough, the liquid thereby being directed into said inner trough by said directing means.

4. The combination of elements as in claim 3 in which said fluid-pressure applying means comprises means for conducting steam at a pressure above that of the ambient pressure of said container to the interior of said outer trough.

5. The combination of elements as in claim 3 in which said fluid-pressure applying means comprises means for conducting air at a pressure above that of the ambient pressure of said container to the interior of said outer trough.

6. The combination of elements as in claim 3 in which said fluid-pressure applying means comprises means for conducting a mixture of steam and air at a pressure above that of the ambient pressure of said container to the interior of said outer trough.

7. In combination, a centrifugal machine comprising a rotatable basket, a casing enclosing said basket and comprising a curb and inner and outer concentric gutters within said casing and below said curb having respective top openings for receiving curb fluids flung off from said basket against said curb during the centrifuging process, said top openings being so located with respect to said curb that all the curb fluids normally flow into said outer gutter only, the opening in said outer gutter being very narrow but sufficient to permit the passage of fluid therethrough if the opening is not blocked, directing means between the gutters adapted to direct the curb fluids into said inner gutter whenever said opening in the outer gutter is blocked, and means for applying fluid pressure in said outer gutter to such an extent that the opening in said outer gutter is blocked to the passage of curb fluid, said fluid thereby being directed into said inner gutter by said directing means.

8. In combination, a container for liquids comprising inner and outer annular troughs at the base thereof, centrifugal means above said troughs for causing liquid to flow in said container toward said troughs, said troughs being so positioned with respect to said liquid flow that the liquid normally flows into the outer trough only, directing means between said troughs adapted to direct the liquid into the inner trough, means for applying fluid pressure in the outer trough to such an extent that liquid from said centrifugal means is prevented from flowing into the outer trough, the liquid thereby being directed into said inner trough by said directing means, and means for applying simultaneously with said fluid pressure, heat and humidity to said outer gutter to facilitate the flow of liquid in said container.

9. The combination of elements as in claim 8 in which said last-mentioned means comprises means for conducting to said outer trough steam at a pressure above the ambient pressure of said outer trough.

10. In a centrifugal machine, a centrifugal basket with a perforate wall, a surrounding casing comprising a curb for directing downwardly liquids centrifuged from said basket, inner and outer annular troughs below said basket for receiving curb liquids, said troughs being separated by a common annular partition and being so positioned with respect to said curb that all the curb liquids normally flow into the outer trough only, a directing member at the top of said partition extending almost to the inner wall of said casing to greatly restrict the opening in said outer trough and positioned to direct curb liquids into said inner trough whenever the opening in said outer trough is blocked, and means for applying fluid pressure in the outer trough to such an extent that the opening therein is blocked and curb liquids are thereby prevented from flowing into the outer trough, whereby the liquids are directed into said inner trough by said directing member.

11. The combination of elements as in claim 10 in further combination with a multiplicity of spaced members for stopping up portions of said opening in the outer trough to further restrict the effective area of said opening.

12. The combination of elements as in claim 10 in further combination with a multiplicity of spaced members for stopping up portions of said opening in the outer trough to further restrict the effective area of said opening, at least some of said spaced members being tapered upwardly to a peak so as to direct curb liquids striking them downwardly into the outer trough.

13. In combination, a container for liquids comprising inner and outer annular troughs at the base thereof, centrifugal means above said troughs for causing liquid to flow in said container toward said troughs, said troughs being so positioned with respect to said liquid flow that the liquid normally flows into the outer trough only, directing means between said troughs adapted to direct the liquid into the inner trough, means for applying during desired time intervals only fluid pressure in the outer trough to such an extent that liquid from said centrifugal means is prevented from flowing into the outer trough during said intervals, the liquid thereby being directed into said inner trough by said directing means, and means for applying, in place of said first-mentioned fluid pressure and during time intervals which are different from said first-mentioned time intervals, fluid pressure in said outer trough which is below the normal pressure in said container.
